UNITED STATES PATENT OFFICE.

WILLIAM LANG, OF BROOKLYN, NEW YORK.

COIN-CONTROLLED VENDING APPARATUS.

SPECIFICATION forming part of Letters Patent No. 431,367, dated July 1, 1890.

Application filed March 18, 1890. Serial No. 343,776. (No model.)

To all whom it may concern:

Be it known that I, WILLIAM LANG, of Brooklyn, in the county of Kings and State of New York, a citizen of the United States, 55 have invented certain new and useful Improvements in Coin-Controlled Vending Apparatus, of which the following is a specification.

This invention has reference to an automatic coin-controlled vending apparatus of that class in which the merchandise is delivered only when a coin of the proper weight is dropped into the coin-slot, said coin being conducted to a scale-beam by which the locking mechanism of the merchandise-delivery slide is released; and the invention consists of a coin-controlled vending apparatus in which the coin is conveyed from the coin-chute by a tilting wheel onto an oscillating scale-beam, which is actuated when a coin of the proper weight has been dropped so as to release the delivery-slide and permit the dropping of an article of merchandise from the merchandise-chute to the delivery-chute. The 60 coin-pan of the scale-beam is constructed with parallel ribs, which are engaged by a tongue at the lower end of a plate attached to the delivery-slide, said tongue locking the scale-beam in position and pushing the coin either 65 into the coin-receptacle or to the delivery-chute, while a releasing mechanism conducts the merchandise to the outside of the apparatus, or locks the delivery-slide, so that no merchandise is delivered.

The invention consists, further, of certain details in the construction of the different parts of the vending apparatus, which will be fully described hereinafter and finally pointed out in the claims.

In the accompanying drawings, Figure 1 represents a front elevation of my improved coin-controlled vending apparatus. Fig. 2 is a vertical transverse section of the same, taken on line 5 5, Fig. 5. Fig. 3 is a vertical longitudinal section on the line 1 1, Fig. 2. Fig. 4 is also a vertical longitudinal section on the line 2 2, Fig. 2, as seen from the opposite side. Fig. 4^a, 4^b, and 4^c are details showing the locking arrangement of the scale-beam, which is called into action when a coin is dropped on the receiving-pan of the scale-beam; and Fig.

5 is a plan view, partly in horizontal section, on line 3 3, Fig. 2.

Similar letters of reference indicate corresponding parts.

Referring to the drawings, A represents the casing of my improved coin-controlled vending apparatus, which casing is provided with a hinged door A' for giving access to the interior of the apparatus.

At the interior of the casing A is arranged a vertical merchandise-chute B, in which the chocolate or other articles are placed, said articles being moved in downward direction by a weighted block b, that is placed on the uppermost article in said chute B. Below the lower end of the merchandise-chute B is arranged a merchandise-delivery slide C, which is guided in suitable ways b', and which is provided with an opening b², that corresponds in size with the mouth of the merchandise-chute, so as to take up an article of merchandise when the opening b² is vertically below the same. A fixed stop d at the rear part of the casing A prevents the delivery-slide C from being pushed in only so far that its opening b² is vertically below the mouth of the delivery-chute B. The delivery-chute D extends from a point in front of the merchandise-chute through an opening in the lower part of the front wall of the apparatus to the outside of the same. The delivery-slide C is moved in forward direction by a slide-rod E, which extends through the front wall of the apparatus, and which is provided with a handle at the front end, the slide-rod being acted upon by a strong spiral spring e, that is interposed between a fixed point on the slide-rod and a fixed transverse guide-bar e' of the casing A.

To the slide-rod E is attached a vertical arm E', which carries a vertical plate E², that is connected by an angular rod E³ with a slot e³ at the rear part of the delivery-slide C, as shown clearly in Fig. 5. The delivery-slide C is prevented from being moved forward by the slide-rod E by means of a coin-controlled locking and releasing mechanism, which consists of two fulcrumed scale-beams F F', which are connected at their front ends by a pivoted frame F² and balanced by a weight attached to the rear end of the lower scale-beam F'. 90 95 100

The front frame F² carries at its upper end

the coin-receiving pan *f*. The coin-receiving pan *f* is provided with a central U-shaped shank *f'*, which is ribbed or serrated at one side, the U-shaped shank being wide enough 5 to permit the plate *E*², that is attached to the arm *E'* of the slide-rod *E*, to enter into said shank. The serrations of the shank *f'* serve to engage a projection or tooth *f*² at the lower end of said plate *E*², when the same is moved 10 forward with the slide-rod *E*, as shown in Fig. 4^c.

To the vertical arm *E'* of the plate *E*² is attached sidewise to and parallel with the slide-rod *E* a fixed rod *e*^x, which serves, in 15 connection with a fixed plate *e*⁴, attached to the pivot-frame *F*², to arrest the forward motion of the slide-rod *E* and delivery-slide *C*, when the former is pulled and moved in forward direction against the tension of the spiral 20 spring *e*. When a coin of the proper size is delivered to the coin-receiving pan *f*, so that the scale-beams are lowered until the lower scale-beam abuts against a stop-pin *e*⁷ of the casing, an opening *e*⁵ in the plate *e*⁴ is placed 25 in line with the longitudinal rod *e*^x and an opening *e*⁶ of the transverse guide-bar *e'*, so that the slide-rod *E* can be moved forward, together with the delivery-slide *C*, which latter carries along a piece of merchandise and 30 drops in front of the delivery-chute, along which it moves to the outside of the casing. The coin is pushed by the plate *E*² forward, so as to be dropped from the pan *f* into a coin- 35 receptacle *R* in front of the scale-beam *F* *F'*.

In the front wall of the casing *A* is arranged a vertical coin-slot *g*, through which a coin of the proper size can be inserted. It is then conducted along an inclined coin-chute *g*², having a slotted disk-shaped front 40 end *g*¹ immediately back of the coin-slot into a pocket *g*³ of a centrally-pivoted tilting wheel *G*, that is guided by an arc-shaped slot *g*⁴ on a fixed guide-pin *g*⁵, as shown in Fig. 4. The mouth of the coin-pocket *g*³ registers 45 with the lower end of the coin-chute when the disk *G* is in a normal position of rest, while said disk is tilted as soon as a coin is delivered into the said pocket, so as to tilt said disk and drop the coin onto one side of 50 the coin-receiving pan *f*, which slide is provided with pins *f*^x, (shown in Fig. 4^c), against which the coin abuts, so that it is tilted over on the coin-pan *f*. The disk *G* is returned 55 to its normal position, so that the coin-pocket registers with the lower end of the inclined coin-chute by the plate *E*² when the delivery-slide is moved forward, said plate engaging a projecting pin *g*⁶ of the tilting disk *G*. The motion of said tilting disk is controlled by 60 the arc-shaped slot *g*⁴, that is guided along a fixed pin *g*⁵ of a supporting-plate.

The coin is prevented from dropping from the pocket *g*³ during the tilting of the disk *G* by means of a retaining-plate *g*⁷, that is attached to the lower end of the coin-chute and provided with guard-pins *g*⁸, as shown in Fig. 3. When a coin of smaller than the required

weight is dropped into the coin-slot, the coin lowers the scale-beams only in part, so that consequently the perforation *e*⁵ of the plate *e*⁴ is not brought in line with the stop-rod *e*^x. Consequently the vertical plate *E*² is compelled to enter into the serrated shank of the coin-pan nearer to the bottom of the same, as shown in Fig. 4^a, so that the delivery-slide 75 cannot be moved forward for delivering an article of merchandise, owing to the abutting of the rod *e*^x against the plate *e*⁴, while at the same time the coin is pushed by the plate *E*² over a curved wall that extends over the coin-receptacle and from the same over a laterally-bent guard-piece *p* to the delivery-chute, so as to be returned to the outside of the apparatus to the party who dropped the coin. In this position of the vertical plate *E*² the projection or tooth at its lower edge serves to lock the scale-beams and the coin-receiving pan *f* in the position in which they are placed by the light-weighted coin dropped on the pan, so that the scale-beams cannot be moved 80 except by pushing the slide-rod *E* and the plate *E*² back into their normal position. When, however, a coin of the proper size and weight is dropped into the coin-slot and conveyed by the tilting pocket onto the coin-pan, 85 the scale-beams are tilted and lowered to their full extent, so that the hole *e*⁵ in the plate *e*⁴ is in line with the stop-rod *e*^x and with the hole *e*⁶ of the guide-bar *e'*. The stop-rod *e*^x passes then through the holes *e*⁵ *e*⁶, when the 90 slide-rod *E* is drawn outwardly to its full extent, so that the merchandise is delivered by the slide from the merchandise-chute to the delivery-chute, from which it is removed by the party dropping the coin. The projection 95 or tooth *f*² of the vertical plate *E*² enters at the upper part of the recessed and serrated shank *f'*, as shown in Fig. 4^b, so as to push the coin forward and drop it below the curved wall of the coin-receptacle *R* into the latter, 100 which before was not possible, as the scale-beams were not tilted sufficiently, so that the pan *f* was entirely below the upper edge of said curved wall, as shown in Fig. 4^a. The coin-receptacle *R* is guided in lateral ways 105 back of the front wall of the casing *A*, and can be readily removed either through the side wall of the same or by opening the front wall, so as to remove from time to time the coin dropped into the apparatus.

For the purpose of preventing the dropping of a coin after all the articles in the merchandise-chute have been delivered, the following arrangement is used. The weight *b*, by which the merchandise is moved in downward direction, is provided with a T-shaped lug *b*³, which is guided in a slot in the side wall of the coin-chute *B* and extended to the outside of the same. The lug *b*³ moves along a vertical rod *H*, which is pivoted at its lower end 110 in suitable bearings *h*, that are supported in a suitable manner at the interior of the apparatus. A spiral spring *h*' is placed on the pivot, one end of said spring being attached

to said rod H above the pivot of the same, so as to press said rod against the head b³ of the block b. A horizontal arm H' extends in forward direction from the pivot-rod I and terminates back of the slotted disk g', that forms the end of the inclined coin-chute g³. The pivoted rod H is provided at its lower part with a cam-shaped enlargement h², (shown in Fig. 2,) against which the head b³ of the block b presses when the same arrives at the lower part of the coin-chute B, so that the rod H is moved sidewise against the tension of its spring h', and thereby the front end of its horizontal arm H' moved across the inner coin-slot, so as to prevent the insertion of a coin from the outside. The coin-chute g³ is open at that side, so as to permit the arm H' to be placed in line with the inner guide-slot. A fixed plate H², below the arm H', serves to guide the arm H' and support it in position. When the arm H' is placed across the inner guide-slot, no coin can be inserted, and consequently no merchandise delivered until the coin-chute is filled again and the stop-arm 25 returned into its former position. In this manner the operation of the apparatus is prevented when the supply of merchandise in the same is exhausted, the arm H' serving at the same time as an indicator that shows that the apparatus has to be refilled with merchandise.

Having thus described my invention, I claim as new and desire to secure by Letters Patent—

- 35 1. The combination of a merchandise-chute, a delivery-slide having an opening communicating with the merchandise-chute, a spring-actuated slide-rod connected with said delivery-slide, a weighted scale-beam having a 40 coin-receiving pan, a coin-conducting chute, and a stop device applied to the scale-beam and adapted to arrest the slide-rod when a coin of less than the required weight is dropped on the scale-pan, substantially as set forth.
- 45 2. The combination of a merchandise-chute, a delivery-slide having an opening communicating with the merchandise-chute, a spring-actuated slide-rod connected with the delivery-slide, a weighted scale-beam having a coin-receiving pan, an inclined coin-chute, a tilting coin-pocket for delivering the coin from the coin-chute to the scale-pan, and a stop device applied to the scale-beam, said stop 50 device arresting the slide-rod until a coin of proper weight is delivered to the scale-pan, substantially as set forth.

3. The combination of an inclined coin-chute, a tilting coin-pocket, and a weighted scale-beam having a coin-receiving pan, substantially as set forth. 60

4. The combination of a merchandise-chute, a delivery-slide having an opening communicating with the merchandise-chute, a spring-actuated slide-rod connected with the delivery-slide, a weighted scale-beam having a coin-receiving pan, a perforated plate attached to the scale-beam, a stop-rod attached to the slide-rod, and a coin-delivering chute for conducting the coin to the scale-pan and lowering the scale-beam, so as to bring the stop-rod in line with the perforation of the plate when a coin of the required weight is delivered to the scale-pan, substantially as set forth. 65

5. The combination of a merchandise-chute, a delivery-slide having an opening communicating with said chute, a spring-actuated slide-rod connected with said delivery-slide, a vertical locking-plate attached to the slide-rod and having a projection at the lower part, a weighted scale-beam, a coin-receiving scale-pan having a centrally recessed and serrated shank that is engaged by said locking-plate, a perforated stop-plate on the scale-beam, and a stop-rod supported on the slide-rod, substantially as set forth. 70

6. The combination of the inclined coin-chute, a tilting coin-pocket having a projecting pin, and a spring-actuated slide-rod connected to the delivery-slide and provided with a vertical plate in line with the projecting pin, said plate serving to return the coin-pocket into its normal position after tilting, substantially as set forth. 75

7. The combination of a merchandise-chute having a slotted side wall, a weighted block fitted in said chute and provided with a head extending through the slotted wall, a pivoted and spring-actuated rod having a cam at the lower end, a forward-extending arm attached to the pivot-rod, and a coin-chute open at one side and having a slotted disk at the front end, said arm being placed across the coin-slot of the disk when the weighted block engages the cam end of the pivot-rod, substantially as set forth. 80

In testimony that I claim the foregoing as my invention I have signed my name in presence of two subscribing witnesses.

WILLIAM LANG.
